CLAIM

The ornamental design for a wood splitting wedge, as shown and described.

DESCRIPTION

FIG. 1 is a left side elevational view of a wood splitting wedge;

FIG. 2 is a rear elevational view thereof;

FIG. 3 is a front elevational view thereof;

FIG. 4 is a top plan view thereof, the bottom view appearing the same; and,

FIG. 5 is a perspective view thereof.

The broken line showing of the handle is for illustrative purposes only and forms no part of the claimed design.

FIG.4

FIG.2

FIG.1

FIG.3
